UNITED STATES PATENT OFFICE

2,180,780

WINDOW SCREEN

Austin P. Summers, Spokane, Wash., assignor of
one-half to Carl G. Ekholm, Spokane, Wash.

Application September 7, 1938, Serial No. 228,858

1 Claim. (Cl. 156—39)

This invention relates to window screens and it is one object of the invention to provide screens carried by spring rollers so mounted at upper and lower ends of a window frame that the screens may be connected with the window sashes and unwound as the sashes are shifted to open position and rewound upon their rollers as the sashes are closed. It will thus be seen that the screens will be out of the way when the sashes are closed and moved into position to prevent flies and other insects entering a room when the sashes are moved to open position.

Another object of the invention is to so connect the lower screen with the lower window sash that it may be released therefrom when desired and thus permit raising of the lower sash without the screen obstructing the window when this is desirable.

Another object of the invention is to provide roller screens which may be easily applied to a window frame of conventional construction connected with sashes slidably mounted therein.

The invention is illustrated in the accompanying drawing, wherein:

Fig. 1 is a sectional perspective view showing roller screens of the improved construction applied to a window frame and connected with the window sashes.

Fig. 2 is a vertical sectional view taken at right angles to Fig. 1.

Fig. 3 is a transverse sectional view on the line 3—3 of Fig. 2 and illustrating the manner in which the lower screen is detachably connected with the lower sash.

Fig. 4 is a fragmentary sectional view taken on the line 4—4 of Fig. 2.

Fig. 5 is a fragmentary view illustrating a modified means for detachably connecting the lower screen with the lower sash.

The window frame 1 to which the screens have been shown applied has its upper and lower cross bars 2 and 3 provided with slots 4 and 5 and its side bars 6 provided with channels or tracks to slidably receive the upper and lower sashes 7 and 8. A housing 9 is mounted upon the upper cross bar 2 in enclosing relation to the slot 4 and a similar housing 10 is secured against the under face of the lower cross bar 3 in enclosing relation to the slot 5. These housings may be secured in any manner desired and within the housings are mounted spring rollers 11 and 12 which are of the usual construction used for roller curtains and are provided with pivot pins and spring winding keys at their ends 55 for winding their springs when the rollers are

rotated in a direction to unwind the sheets of wire screening 13 and 14 which are wound upon the rollers. A metal binding 15 is provided for the outer end of the upper screening 13 and after this end portion of the screening has been drawn out through the slot 4 of the upper cross bar 2 it is fitted into the groove 16 formed in the upper end bar 17 of the sash 7 where it is firmly secured by rivets 18 passed transversely through the end bar. Therefore, when the upper sash 10 is shifted downwardly to open position the upper screen will be drawn downwardly with it into position to prevent insects from passing inwardly through the window frame above the lowered upper sash. Each of the side bars 6 of the frame 1 is formed with a groove 19 to receive the adjacent marginal portion of the screening 13 so that the insects cannot enter between the sides of the frame and the side edges of the screening, and upon referring to Fig. 4, it will be seen that the grooves are substantially V-shaped in cross section to provide restricted entrances through which the marginal portions of the screening project. Lugs 20 are fixed to marginal edge portions of the screening in spaced relation to each other longitudinally thereof to prevent the marginal portions of the screening from being forced out of the grooves 19 by the force of wind or due to someone accidentally pressing upon the screening when it is in extended position for use.

The lower screening 14 is passed upwardly through the slot 5 in the lower cross bar 13 of the window frame and is provided with a binding 21 formed from a folded strip of sheet metal which is welded or otherwise firmly secured to the screening, as shown in Fig. 3. This binding 21 projects upwardly from the lower cross bar 3 and is received in a groove 22 formed along the under face of the lower end bar 23 of the lower sash 8. The binding fits in the groove 22 with sufficient looseness to permit easy removal therefrom and in order to releasably secure it in the groove, there have been provided fasteners 24 carried by and spaced from each other longitudinally of the end bar 23 of the lower sash. Each of the fasteners 24 is formed as shown in Fig. 3, and consists of a cup or socket 25 countersunk in the end bar 23 and carrying a pin 26 which is slideable longitudinally and yieldably held against outward movement by a spring 27. A head 28 is formed at the outer end of the pin in order that the pin may be grasped and drawn outwardly from a position in which its inner end portion passes through an opening 29 formed 55

through the binding. The spring yieldably holds the pin in operative position and securely retains the binding in the groove 22 of the sash so that the screening will be drawn upwardly with the 5 lower sash, but by grasping the head and exerting outward pull the pin may be drawn out of the opening 29 and when both of the fasteners 24 are in the releasing position the screening will be freed from the sash and the sash may be 10 raised without unrolling the screening from the roller. The window opening will then be clear. Similar fasteners may be provided for securing the upper screen to the upper sash if desired. Lugs 30 corresponding to the lugs 20 are provided 15 along side edges of the lower screen to engage in grooves formed in the sash and prevent this screen from being pressed through the window opening out of its proper position. When the lower screening is released from the lower 20 sash, its binding must be prevented from passing entirely through the slot of the lower cross bar 3 of the window frame as otherwise it would be out of reach and could not be again connected with the lower sash. In order to do so, there 25 has been provided a bracket 31 secured against the under face of the lower bar 3 and projecting slightly across the slot into position for its projecting end to engage the lower edge of the binding and limit downwardly movement of said 30 binding through the slot, as shown in Fig. 3. At its free end, the abutment bracket is provided with a depending bill 32 which acts as a guide and permits the screening to move past the bracket without danger of being torn by catching 35 against the bracket.

Instead of connecting the lower screen with the lower sash by means of the fasteners 24, fastening means such as shown in Fig. 5 may be employed. In this figure, the lower end bar of the lower sash is formed with slots 33 which extend longitudinally of the end bar in the same locations as the fasteners and these slots communicate with the groove 22 into which the binding 21 of the screening fits. Slots 34 resembling bayonet slots, are formed in the binding in position to register with the slots 33 as the binding is passed upwardly into the groove and through the slots are mounted pins 35 having heads at their outer ends so that they may be

easily slid longitudinally of the slots 33 into and out of position to engage the slots 34 and securely but releasably hold the binding in the groove.

When this improved screen is in use, the upper and lower bars of the window frame are formed with slots and after the rollers carrying the screening sheets are mounted in the housings, these housings are secured to the bars in enclosing relation to the slots. The sheets of screening have their bound ends passed outwardly through the slots and secured in the grooves formed in the end bars of the upper and lower sashes and when the sashes are shifted to open position the screening sheets will be drawn outwardly to block the window opening between the 15 sashes and ends of the window frame. When the sashes are slid to closed position, the spring rollers will rewind the screening and a clear view through the window panes will not be obstructed by screens. When it is desired to open the lower sash without withdrawing the screen, it is merely necessary to move the fasteners to a releasing position and the binding 21 will be released and the sash may then be slid upwardly to open position without withdrawing the screen from the lower 20 housing.

Having thus described the invention, what is claimed is:

A window frame having a cross bar formed with a longitudinal slot, a sash slidable in said frame and having an end bar formed with a groove confronting the slot, a housing carried by said cross bar and enclosing the slot, a rewind roller in said housing, a sheet of screening wound upon said roller and projecting out through the 30 slot, a binding for the outer end of said screening engaged in said groove, said binding being formed with a longitudinal slot having a lateral entrance through the outer side edge of the binding, the end bar of said sash having a longitudinal slot 35 therein registering with the slot of the binding when the binding is seated within the groove, and a fastener passing through the slot of the end bar and shiftable longitudinally therein into and out of position to engage through the slot 40 of the binding and releasably secure the binding 45 in the groove of the end bar of the sash.

AUSTIN P. SUMMERS.
